US0D1016755S

(12) **United States Design Patent** (10) **Patent No.:** **US D1,016,755 S**
(45) **Date of Patent:** **** Mar. 5, 2024**

(54) **SOCKET**

(71) Applicant: **DONGGUAN GETIAN ELECTRICAL APPLIANCE MANUFACTURING CO., LTD.**, Guangdong (CN)

(72) Inventor: **Xiaoxiong Chen**, Guangdong (CN)

(73) Assignee: **DONGGUAN GETIAN ELECTRICAL APPLIANCE MANUFACTURING CO., LTD.**, Guangdong (CN)

(**) Term: **15 Years**

(21) Appl. No.: **29/818,683**

(22) Filed: **Dec. 9, 2021**

(51) LOC (14) Cl. **13-03**

(52) U.S. Cl. **USPC D13/137.2**

(58) **Field of Classification Search**

(57) **CLAIM**

The ornamental design for a socket, as shown and described.

DESCRIPTION

FIG. 1 is a front, right and top perspective view of a socket, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged partial view of the area labeled 9 in FIG. 1.

The dash-dash broken lines shown in the drawings are included for the purpose of illustrating portions of the article that form no part of the claimed design.

The dash-dot broken lines shown in the drawings are included for the purpose of illustrating the bounds of the partial views and form no part of the claimed design.

1 Claim, 9 Drawing Sheets
